PROCESS FOR REDUCTION OF ORGANIC DISULPHIDES

Marcia Gutcho and Louis Laufer, Bronx, N. Y., assignors, by mesne assignments, to the United States of America as represented by the Secretary of the Navy

No Drawing. Application October 30, 1953
Serial No. 389,479

10 Claims. (Cl. 260—112)

The present invention is concerned with the reduction of organic disulfide compounds of the general class RSSR' where R and R' may be amino acid, peptide, alkyl or aryl group or other organic radical to their respective thiols, RSH and R'SH.

As conducive to a clear understanding of the invention, it is noted that disulfides of amino acids and peptides such as cystine, diglutathione, diglutamylcystine, cysteinyl diglycine and related cystine peptides may be reduced by cyanide, or sodium amalgam but these reactions are incomplete and form undesirable by-products resulting in poor yields. Alkyl and aryl disulfides are reduced to respective thiols by hydrogen in the presence of metallic sulfides, but only under conditions of high pressure and elevated temperature.

It is accordingly among the objects of the invention to provide a process for the reduction of organic disulfides to their respective thiol forms rapidly and in good yield by the use of inexpensive reagents and without resort to high pressure or high temperatures.

Another object is to provide a method whereby disulfides may be eliminated from mixtures containing them by converting such disulfides to their respective thiol forms so that they may be removed more readily from such mixtures as insoluble metal mercaptides.

A further object is to accomplish reduction of organic disulfide under conditions of pH and temperature which are conducive to stability of the free thiol thus formed, such thiols being generally more resistant to reoxidation to disulfides at acidic pH (below 7 and preferably below 5.0) and at low temperatures.

For example, dithioethanolamine

is highly toxic, but the reduced thiol

has been reported to have useful therapeutic properties. Also, many heat sensitive, enzymatically active proteins are inactivated by the formation of disulfides and may be reactivated by reducing the S—S linkages essential to enzyme activity to the free SH (thiol) form at temperatures below 60° C.

In the refining of petroleum products, it is frequently necessary to remove aliphatic and aromatic disulfides to avoid poisoning of catalysts used in subsequent processing. Furthermore, sulfur compounds may produce corrosive decomposition products when present in motor fuels or lubricants. As a step in removal of disulfides from petroleum mixtures, it is convenient first to reduce them to free thiols so that they may be removed more readily as insoluble metal mercaptides.

In the preparation of sulfhydryl amino acids and peptides which are useful in nutrition and medical treatment, such as cysteine and glutathione, yields are frequently markedly reduced by formation of disulfides during proc-

essing, which is difficult to avoid. The invention provides a means of converting such disulfides to the desired end products in the thiol form above referred to.

The invention from one important aspect thereof, utilizes the surprising discovery that metallic sulfides, particularly those of bismuth, lead and mercury, or other acid insoluble metal sulfide of molecular weight greater than 60, catalyze a reaction between hydrogen sulfide and organic disulfides in an aqueous medium which reaction results in rapid reduction of such disulfides to their respective thiol forms. This reaction proceeds whether the metallic sulfide is formed in situ or is prepared in advance and added to the reaction mixture, and is operative at substantially atmospheric pressure and temperatures below 100° C. In the absence of such metal sulfide catalyst, the reaction with H₂S proceeds if at all at rates not industrially practical.

In one embodiment of the invention, water-soluble salts of lead, mercury or bismuth are added to aqueous solutions of peptide disulfides such as cystine, diglutamylcystine, cysteinyl diglycine or the disulfide form of glutathione, with or without addition of acid, and H₂S is passed through the solution at room temperature and atmospheric pressure. The insoluble metal sulfide is formed promptly in situ, and promptly and progressively effects formation of the respective thiol forms in the reaction mixture as gassing continues.

In another embodiment of this invention insoluble metal sulfide catalyst is prepared by passing H₂S through a solution of a soluble salt of the desired metal causing precipitation of the insoluble metal sulfide which is subsequently dispersed into the reaction mixture.

Disulfides which form salts of the metals lead, mercury or bismuth, such as amino acids and peptides, may be converted, first to such metal salts and then treated either in solution or suspension with H₂S, thus carrying out in situ the decomposition of such metal salt and the formation of the metal sulfide which thereupon catalyzes the reduction of the free disulfide to the thiol form.

The concentration of disulfide is not critical, being largely a matter of convenience and depending upon the solubility of the disulfide compound or compounds in the reaction mixture. In the aqueous systems used, concentrations from 2 to 30% are preferred. In mixtures where the desired end is the removal of undesirable disulfide components, the concentrations of such compounds may be as little as 0.1%.

In aqueous systems acidification to a pH below 5 is desirable because the metal sulfides generally precipitate more effectively and thiols are less susceptible to reoxidation in subsequent processing if the medium is acid.

The molar ratio of metal sulfide to disulfide present may be from 0.01 to 1, preferably 0.01 to 0.1.

The H₂S is added most conveniently by diffusing the gas under the surface of the reaction mixture at a rate just sufficient to maintain the mixture saturated in respect to H₂S and provide a slight excess.

While the foregoing description is believed adequate to meet statutory requirements, a few specific examples will nevertheless now be set forth.

Example I

To 10 parts by weight of a 6% aqueous solution of oxidized glutathione (GSSG) having a natural pH of about 2.5, is added 1 part of a 10% solution of lead acetate tri-hydrate Pb(C₂H₃O)₂·3H₂O. A capillary gas diffusing tube is inserted into the liquid and H₂S passed into the solution. After sixty minutes, assay of the reaction mixture indicates that 80% of the GSSG has been reduced to GSH. After removal of the PbS which precipitates on gassing, the GSH may be recovered from the solution as its insoluble cuprous salt.

Example II

H_2S gas is passed through a mercuric chloride solution in which the mercury salt has been brought into solution by addition of sufficient concentrated HCl , until all of the mercury present is precipitated as HgS . The precipitate is then separated, washed and added as a water suspension to a 2% solution of cystine in 0.1 N HCl . H_2S gas is passed into the reaction mixture at room temperature. After one hour 75% of the cystine is converted to cysteine which may be recovered by conventional procedure.

Example III

Freshly precipitated Bi_2S_3 is prepared by passing H_2S through a 5% aqueous solution of $Bi(NO_3)_3 \cdot 5H_2O$ to which in order of 1% by volume of concentrated HNO_3 has been added. The precipitate is washed and the aqueous phase displaced by several washings with toluene. 1 part by weight of the toluene- Bi_2S_3 suspension is then added to 10 parts of a 10% solution of 2,2-dihydroxy 6,6-dinaphthyl disulfide:

and H_2S is bubbled through the reaction mixture. After two hours, 70% of the disulfide has been converted to the thiol form:

As many changes could be made in the above process and many apparently widely different embodiments of this invention could be made without departing from the scope of the claims, it is intended that all matter contained in the above description shall be interpreted as illustrative and not in a limiting sense.

Having thus described our invention, what we claim as new and desire to secure by Letters Patent of the United States is:

1. The process for reducing disulfide groups in organic disulfide compounds of the class consisting of cystine, peptides of cystine, and proteins containing cystine, to the corresponding sulfhydryl form, in an aqueous medium by treatment with hydrogen sulfide in the presence of a sulfide of a metal selected from the group consisting of mercury, bismuth and lead, at atmospheric pressure and at a temperature below 100° C.

2. The process defined in claim 1 in which the molar ratio of the metal sulfide to the organic disulfide is between .01 and 1.

3. The process defined in claim 1 in which the molar ratio of the metal sulfide to the organic disulfide is between .01 and 0.1.
4. The process defined in claim 1 in which the aqueous medium has a pH below 7.0.
5. The process defined in claim 1 in which the temperature is maintained below 60° C.
6. The process for reactivating by reduction enzyme proteins inactivated by reason of denaturation to the disulfide form, comprising the treatment of such inactivated proteins with hydrogen sulfide in aqueous medium in the presence of a metal sulfide selected from the group consisting of HgS , PbS , Bi_2S_3 at temperature below 60° C. and at substantially atmospheric pressure.
- 10 7. The process for reduction of cystine disulfide bonds in peptides containing the same by treatment with hydrogen sulfide in an aqueous medium in the presence of a sulfide of metal selected from the group consisting of mercury, lead and bismuth in a molar ratio of 0.01 to 1.0 per mol of the peptide disulfide at a temperature below 100° C. and at atmospheric pressure.
- 15 8. The process for reducing cystine by treatment with hydrogen sulfide in an aqueous medium having a pH below 5.0 in the presence of a sulfide of a metal from the group consisting of mercury, bismuth and lead in the molar ratio of .01 to 1.0 per mol of the cystine at a temperature below 60° C. and at atmospheric pressure.
- 20 9. The process for reducing cystine disulfide bonds in glutathione disulfide by treatment with hydrogen sulfide in an aqueous medium having a pH below 5.0 in the presence of a sulfide of a metal from the group consisting of mercury, bismuth and lead in the molar ratio of .01 to 1.0 per mol of the glutathione disulfide at a temperature below 60° C. and at atmospheric pressure.
- 25 30 10. A process for reducing cystine disulfide bonds in proteins containing the same, comprising the treatment of said proteins in an aqueous medium at a pH below 7.0 with hydrogen sulfide in the presence of a sulfide of a metal selected from the group consisting of mercury, lead and bismuth, in the molar ratio of from 0.1 to 1.0 per mol of disulfide present, at a temperature below 60° and at atmospheric pressure.
